MOTOR FOR PUMPING MECHANISMS

Wade H. Wineman, Michigan City, Ind., assignor
to Sullivan Machinery Company, a corporation
of Massachusetts

Application October 9, 1934, Serial No. 747,538

29 Claims. (Cl. 121—126)

This invention relates to pumping mechanisms and more particularly to expansible chamber motors which are well adapted for a number of purposes but which find particular utility in the operation of oil well pumps.

In certain oil fields there is a substantial quantity of oil available but insufficient pressure in the strata to cause the oil to rise to the surface, and under such conditions devices for pumping the oil are necessary. A very satisfactory system includes a number of pumping units arranged around and severally supplied with power-operating medium from a central air compressor having pipes extending therefrom to the several pumping unit motors. The unit at each well in this system includes a pump head in the form of an expansible chamber motor, and the latter is connected with a piston type or other suitable pump in the well. For maximum economy the air is customarily supplied to the pump operating motors after preheating at the well and is exhausted from the motor cylinders with considerable residual pressure (sufficient properly to counter-balance the weights of the pump rod line and moving pump parts) and is returned to the intake of the air compressor of the compressor plant for recompression. Suitable make-up means is provided for supplying additional air, as some is lost through leakage, or the like.

It is not practical to have an operator at each well, for reasons of economy, and it is accordingly important that the pumping motors shall be very reliable, free from possibility of derangement under all ordinary conditions; and it is desirable if practicable, to provide a motor which may both operate upon a rectangular cycle and also with expansion and compression in accordance with the conditions under which it is to be used.

An object of the present invention is to provide an improved pumping motor particularly adapted for oil well pumping as described, but of general applicability wherever relatively long and comparatively slow strokes are desired. Another object of the invention is to provide an improved single-acting motor of the expansible chamber type having improved valve means. A further object of my invention is to provide an improved fluid-operated valve gear for an expansible chamber motor. Still another object of my invention is to provide an improved fluid-operated valve gear of the poppet type for an expansible chamber motor. Other objects and advantages of the invention will hereinafter more fully appear.

In the accompanying drawings, in which one illustrative embodiment and a modification of the invention have been shown for purposes of illustration,—

Fig. 1 is a front elevation, with parts broken away, showing a portion of the pumping mechanism arranged at a well which is to be pumped and incorporating a pumping motor of the illustrative form. 5

Fig. 2 is a view on an enlarged scale with parts broken away to show a central section through a portion of the motor cylinder and through the valve mechanism of the illustrative embodiment of the improved expansible chamber motor herein described. 10

Fig. 3 is an enlarged sectional view through the inlet valve mechanism of the motor. 15

Fig. 4 is a top view of the inlet valve chest.

Fig. 5 is a fragmentary detail section through a portion of the motor. 20

Fig. 6 is a detail section through another portion of the motor, the section being at right angles to that of the section of Fig. 5.

Figs. 7, 8, 9 and 10 are views partially in section and partially in elevation showing different phases of the motor cycle. 25

Fig. 11 is a view on a small scale showing a modification.

Referring first to Fig. 1, it will be noted that a platform or derrick floor 1 supports a suitable frame 2 of structural steel or the like. The top member 3 of the frame pivotally supports at 4 the upper head 5 of an expansible chamber motor 6, which includes, in addition to the upper head, a cylinder 7 and a lower head and valve chest member 8. The parts may be suitably held together by threading the parts, or by side rods, not shown, extending between the upper and lower heads and clamping the cylinder between the heads. Associated with the lower head are the admission and exhaust valve mechanisms of the motor, and these control the flow from a compressor (not shown) through a supply pipe 10, a preheater 11, a delivery pipe 12, a stop valve 13, a vent valve 14, an automatic stop or control valve mechanism 15, which is adapted to preclude overspeeding of the motor and which forms the subject matter of my application Serial No. 746,171, filed September 29, 1934, then to the motor; and the exhaust passes from the motor through a line 16, controllable by a valve 17, back to the intake of the compressor. 30

The motor 6 has a piston 18 reciprocable in the cylinder 7 and connected by a piston rod 19 through a suitable adjustable connection 20 to a

pump rod 21 which leads to a pump of the reciprocating type, not shown, disposed in the well. A discharge line 22 is provided to lead away the pumped oil, and the line 23 is provided 5 to conduct away gas from the well head 24.

The admission valve of the motor 6 is of the poppet type and is shown at 25. This valve is provided with a seat 26 surrounding a port 26' formed in a partition 27 between a chamber 28 10 to which the supply connection 12 leads and a passage 29 opening into the bottom of the motor cylinder 7. Valve 25 is suitably connected either flexibly or by an integral stem 30 with a piston mechanism 31, which is reciprocable in a cylinder member 32 alined with the valve seat 26 and 15 supported by the top of the lower cylinder head 8 and having a suitable upper head or end-closure 33. The piston structure 31 comprises a lower portion 34 of smaller diameter (of substantially the same diameter as the port 26') and an upper portion 35 of larger diameter, the portion 34 fitting a bore 36 in cylinder member 32 and the portion 35 fitting a bore 37 in cylinder member 32. Any suitable mode of reducing 20 leakage past the piston portions may be employed, as for example piston rings as shown at 38. The space at the lower end of the larger bore 37 is vented as at 39 and the pressure leaking thereto may be led away to a desired point or conducted directly to atmosphere, as may be 25 desired. The top of the valve member 25 is smaller than larger piston portion 35. The upper head member 33 of the cylinder 32 is provided with a central bore 41 in which a tubular member 42, having a valve seat 43 at its lower end, is mounted. The member 42 may be suitably held in position in the upper head 33 and is connectible by a coupling member 44 to a tube 45 leading upwardly along the side of the cylinder 40 7 and arranged to communicate with the bore of the cylinder at a point 45' where it will be uncovered by the upper end of piston 18 as the latter approaches the bottom of the stroke of the motor cylinder. The piston structure 31 carries in its upper end a central threaded plug 47 45 having a bore 48 therein in which a spring 49 is mounted, and the spring 49 yieldably presses a valve member 50, which is slidably mounted in the upper end of the plug 47, in an upward direction and is adapted to cause the same to protrude normally somewhat above the upper end of the piston portion 35. The valve member 50 is provided with wings 51 to be engaged by the spring 49 and has a tapered seating portion 52 to 50 operate with the seat 43. The spring 49 is of such strength as to enable portion 52 to prevent flow through the tubular member 42, while in contact with valve seat 43. A pin 54 is provided to prevent the plug 47 from becoming unscrewed accidentally during operation of the pump.

The upper head 33 further comprises a radially offset chamber 56 having a liner 57 providing a valve seat 58 surrounding a port which communicates at 59, through the bottom of the head, 55 with the chamber 37. A spring pressed valve 60 having an extension or stem 61 normally seats upon the seat 58, being pressed thereon by a spring 62 maintained under compression by a threaded follower and plug member 63. The 60 spring pressure is such as to prevent any purely pressure fluid differential at the opposite sides of the valve from unseating the latter. The valve is provided with wings 64 for the spring to engage and arranged to permit flow past the valve 65 and through the port 59 when the valve is un-

seated. When the valve is upon its seat the stem 61 projects a substantial distance inwardly from the inner surface of the upper head member 33 and is adapted to be engaged by the upper end of the piston portion 35, which has a wear-resisting material, as shown at 65, arranged in a groove upon the upper end of the piston member so that irrespective of the position the valve 25 may assume by rotation upon its axis there will be no tendency to change the operation of the device 10 due to wearing away of the head of the piston portion 35. The plug 63 is ported at 66 and a connection 67 leads from the port 66 to communicate with the bore of the motor cylinder 7 below the piston either just about as the piston 18 approaches the top of its stroke or somewhat earlier, depending upon the cycle of operation desired and the adjustment of control means hereinafter described.

At the opposite side of the lower head 8 of the 20 motor cylinder there is arranged the exhaust valve mechanism. This includes an exhaust valve 70 which seats upwardly upon a seat 71 surrounding a port 71' formed in a partition member 72 separating a chamber 73 which communicates through the lower cylinder head 8 with the bore of the cylinder 7 and a chamber 74 to which the exhaust conduit 16 is connected. The exhaust valve 70 is provided with a lower stem 75 loosely moving in a guide 76 and is 25 pressed in upward direction by a spring 77, whose tension and function will later be more fully described. The exhaust valve is also provided with an upwardly extending stem 78 which is 30 pressed by spring 77 into end abutment with and so operatively connected with a piston mechanism 79 substantially identical with the piston mechanism described as cooperating with the admission valve. Similar parts bear like numbers, but with primes. The valve-controlled central passage extending through the upper cylinder head 33' of the exhaust valve controlling mechanism is communicable through a connection 80 35 selectively with a point substantially above the top of the piston 18 when the latter is in its lowest position in cylinder 7 or at a point relatively substantially closer to the top of the piston 18 when the latter is in its lowest position, depending upon the cycle of operation desired and the adjustment of control means hereinafter 40 described. The port 66' of the exhaust valve controlling mechanism is connected by a connection 81 with a point just below the motor piston 18 when the latter is at substantially the top of its 45 normal working stroke.

The mechanism for controlling the points of communication of the connections 67 and 80 with the cylinder bore and the means therefor are identical with the means for accomplishing similar functions shown in my copending application Ser. No. 612,538, filed May 20, 1932, (now matured into Letters Patent No. 2,004,146), and it will here suffice to state that by suitable adjustment of the valve mechanisms 83' and 84' arranged respectively in the valve casings 83 and 84 the connection 80 may be caused to communicate with the cylinder bore at the same point that the connection 45 communicates with it, or at a higher point through the connection 80', and the connection 67 may be caused to communicate with the 50 cylinder bore at the same point as the connection 81 or at a materially lower point, through the connection 67', as may be desired. The mode of operation of the apparatus may now be here 55 briefly described.

For the purpose of this description it will be assumed that the valve mechanisms 83 and 84 are so adjusted as to cause the several passages 45, 67, 80 and 81 each to have individual and spaced communication with the cylinder bore. Starting with the position of the parts shown in Fig. 2, it will be observed that the admission valve 25 is unseated (the motor back pressure unseats it before the motor starts) and that operating fluid 10 is flowing from the chamber 28 through the port 26' and through the port 29, beneath the piston 18 and is in the process of raising the latter. It will be observed that the valve 52 is seated upon the valve seat 43 and that no fluid which may 15 enter the connection 45 can obtain access to the bore 31 in which the piston portion 35 is now in uppermost position. When, however, pressure fluid obtains access to the connection 67 the fluid will be able to pass the open valve 60 and act upon 20 the top of the piston portion 35 and start downward movement of the valve 25.

As the piston 18 moves upward in the cylinder, communication with the passage 45 will first be established, but no motion of the admission valve 25 will occur because the valve 52 is seated and is so maintained by the pressure of its spring 49. The connection 80 will thereafter be brought into communication with the pressure acting upon the lower side of the piston, but because the valve 52' 30 of the exhaust control mechanism, corresponding to the valve 52 of the high pressure control mechanism, is also seated and so held by its spring corresponding to the spring 49, the exhaust valve will remain closed.

35 When the piston, however, moves upward to a position where fluid pressure is supplied from the cylinder bore to connection 67, this fluid will pass through the port 66, past the valve 60, through the port 59 and act upon the top end 40 area of the piston portion 35 and start to move the latter downwardly. Before the piston portion 35 moves downwardly far enough to permit closure of the valve 60, valve 52 will unseat and fluid will then flow through the connection 45, 45 and even though its flow through the connection 67 will be terminated on closure of the valve 60, the pressure through 45 will force the piston downward to close the valve 25 upon its seat 26. Cut-off will thus be effected. The piston 18, however, will continue to move upwardly under the action of the expanding working fluid until its lower end passes above the point of communication of the connection 81 with the cylinder bore and thus pressure will be admitted to the chamber 55 within which the controlling piston mechanism of the exhaust valve is located, and the exhaust valve will be unseated against the action of the spring 77.

The piston 18 then will start downward, being 60 moved by the weight of the rod line and against the back pressure. Though the mouth of the port 81 may be uncovered and brought into communication with the atmosphere through the vented top of the motor cylinder at 90, the valve mechanism 65 60' associated with the exhaust control will not, because of the pressure exerted by its spring which corresponds to the spring 62, permit escape of fluid from above the exhaust valve operating piston, and accordingly the exhaust valve will 70 remain open. Similarly the valve 60 will not, because of the pressure exerted by its spring 62, permit the venting of the space above the piston portion 35 when the piston 18 moves below the point of communication of the passage 67 with 75 the motor cylinder.

When the upper surface of the piston passes below the point of communication of the passage 80 with the bore of the cylinder 1, the pressure will be vented from above the piston which has been holding the exhaust valve open and allow 5 the latter to close, it being obvious that this closing action will be occasioned by the combined pressure of the spring 77 and the action of exhaust line pressure upon an area equivalent to the cross section of the smaller bore in the exhaust valve controlling cylinder acting to move the exhaust valve piston upwardly so that the spring 77 and the rush of exhausting air may close valve 70. When, thereafter, the space above the piston 35 is brought into communication with 10 the space above the piston 18 when the latter moves downward below the point of communication of connection 45 with the cylinder bore, the fluid will flow out through the connection 45 to atmospheric pressure and the admission valve 20 will have then only atmospheric pressure acting on the top of the piston portion 35 to maintain it seated, while the pressure within the lower or "working" end of the cylinder, acting upon the lower surface of the valve, will move the latter 25 to open position.

The cycle above explained will then be repeated over and over as long as fluid supply to the motor is continued. It will be noted that valves 60 and 60' do not seat until valves 52 and 52' respectively unseat on downward movements of the valve actuating pistons, and that desirably fluid admitted through ports 59 and 59' can have access to the full top areas of the respective valve controlling pistons.

35 The motor as operating upon a cycle including expansion (between the closure of 25 and the opening of 70) and with compression (between the closing of 70 and the opening of 25) has been described. In Fig. 11 a motor operating only on 40 an approximately rectangular cycle is shown. Here 67 and 81 enter a common T 91 connected at 91' with the cylinder bore, and 45 and 80 enter a common T 92, connected at 92' with the cylinder bore. The admission valve closes before the 45 exhaust valve opens because of the spring 77 and, it is believed, in part because of the pressure differential due to the larger area of the back of the valve 70 than the cross section of piston 34'. The exhaust valve closes before the admission valve 50 opens, in part, because, it is believed, of the uncounter-balanced annulus at the rim of the back of the closed admission valve, and unquestionably because of the spring 77.

In both forms of the invention it will be noted 55 that there are provided a rugged, simple, positive, and efficient valve gear and motor providing for a smooth pumping operation and using a minimum of moving parts and avoiding anything but a positive and definite timing of the events of the 60 motor cycle.

While there are in this application specifically described two forms which the invention may assume in practice, it will be understood that these forms of the same are shown for purposes of 65 illustration and that the invention may be modified and embodied in various other forms without departing from its spirit or the scope of the appended claims.

What I claim as new and desire to secure by 70 Letters Patent is:

1. In a motor, in combination, a cylinder, a piston reciprocable therein, means for continuously venting one end of said cylinder, and means for controlling admission and exhaust with respect to 75

- the opposite end of said cylinder including an admission valve opened by the pressure prevailing in the working end of the cylinder just prior to admission and an end-seating exhaust valve moving on closure in the direction of flow of the discharging exhaust fluid and whose closing is controlled by motor back pressure, and means for moving said valves in the opposite directions by cylinder pressure including a check valve moving with each 5 of said valves and delaying throwing thereof.
2. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and an end-seating exhaust valve moving on closure in the direction of flow 10 of the discharging exhaust fluid and whose closing is controlled by motor back pressure, and means for moving said valves in the opposite directions by cylinder pressure including a check valve moved by each of said valves to a position 15 to permit the passage of valve throwing pressure.
3. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and an end-seating exhaust valve moving on closure in the direction of flow 20 of the discharging exhaust fluid and whose closing is controlled by motor back pressure, and means for moving said valves in the opposite directions by cylinder pressure including check valves 25 respectively moving with and moved by each of such 30 valves and respectively delaying opposite valve movements.
4. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and having a closing pressure-device 35 having a plurality of piston controlled connections with the cylinder bore and respectively providing starting and throwing pressures, said starting pressure connection last uncovered by the piston on the working stroke of the latter.
5. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and having a closing pressure-device 45 having a plurality of piston controlled check-valved connections with the cylinder bore and respectively providing starting and throwing pressures, said starting pressure connection last uncovered by the piston on the working stroke of the latter.
6. In a motor, in combination, a cylinder, a piston reciprocable therein, means for continuously venting one end of said cylinder, and means for controlling admission and exhaust with respect to the opposite end of said cylinder including an admission valve opened by the pressure 50 prevailing in the working end of the cylinder and

just prior to admission and having a pressure device associated therewith for effecting closing thereof, said pressure device having a plurality of check-valve-controlled connections between the same and the cylinder bore at points in the latter overrun by the piston during movements of the same, said connections operative respectively to transmit starting and throwing pressures, the check valve control for one of said connections comprising a check valve element 5 carried by said pressure device and effective to delay the closing of said valve until pressure is transmitted by the other of said connections.

7. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and having a pressure device associated therewith for effecting closing thereof, said pressure device having a plurality of check-valve-controlled connections between the same and the cylinder bore at points in the latter overrun by the piston during movement of the same, said connections operative respectively to transmit starting and throwing pressures, the check valve control for one of said connections comprising a valve relative to which said pressure device is 25 bodily movable but actuated by said pressure device to a position in which pressure is admitted thereby to said pressure device.

8. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and having a pressure device associated therewith for effecting closing thereof, said pressure device having a plurality of check-valve-controlled connections between the same and the cylinder bore at points in the latter overrun by the piston during movement of the same, said connections operative respectively to transmit starting and throwing pressures, the check valve control for one of said connections comprising a check valve element carried by said pressure device and effective to delay the closing of said valve until pressure is transmitted by the other of said connections and the check valve control for the other one of said connections comprising a valve relative to which said pressure device is bodily movable but actuated by said pressure device to a position in which pressure is admitted thereby to said pressure device.

9. In a motor, in combination, a cylinder, a piston reciprocable therein, means for continuously venting one end of said cylinder, and means for controlling admission and exhaust with respect to the opposite end of said cylinder including an exhaust valve whose closing is controlled by motor back pressure and having an opening pressure-device having a plurality of piston controlled connections with the cylinder bore and providing starting and throwing pressures the former last uncovered by the piston on the working stroke thereof.

10. In a motor, in combination, a cylinder, a piston reciprocable therein, means for continuously venting one end of said cylinder, and means for controlling admission and exhaust with respect to the opposite end of said cylinder includ-

ing an exhaust valve whose closing is controlled by motor back pressure and which has a pressure device associated therewith for effecting opening thereof, said pressure device having a plurality of check-valve-controlled connections between the same and the cylinder bore at points in the latter overrun by the piston during movement of the same, said connections operative respectively to transmit starting and throwing pressure, and said 10 connection for providing throwing pressure first uncovered by the piston on the working stroke thereof.

11. In a motor, in combination, a cylinder, a piston reciprocable therein, means for continuously venting one end of said cylinder, and means for controlling admission and exhaust with respect to the opposite end of said cylinder including an exhaust valve whose closing is controlled by motor back pressure and which has a pressure device associated therewith for effecting opening thereof, said pressure device having a plurality of check-valve-controlled connections between the same and the cylinder bore at points in the latter overrun by the piston during movement of the same, the check valve control for one of said connections comprising a check valve element carried by said pressure device and effective to delay the opening of said valve until the transmission of pressure through the other connection.

30 12. In a motor, in combination, a cylinder, a piston reciprocable therein, means for continuously venting one end of said cylinder, and means for controlling admission and exhaust with respect to the opposite end of said cylinder including an exhaust valve whose closing is controlled by motor back pressure and which has a pressure device associated therewith for effecting opening thereof, said pressure device having a plurality of check-valve-controlled connections between the same and the cylinder bore at points in the latter overrun by the piston during movement of the same, the check valve control for one of said connections comprising a valve relative to which said pressure device is bodily movable but actuated by said pressure device to a position in which pressure is admitted thereby to said pressure device.

13. In a motor, in combination, a cylinder, a piston reciprocable therein, means for continuously venting one end of said cylinder, and means for controlling admission and exhaust with respect to the opposite end of said cylinder including an exhaust valve whose closing is controlled by motor back pressure and which has a pressure device associated therewith for effecting opening thereof, said pressure device having a plurality of check-valve-controlled connections between the same and the cylinder bore at points in the latter overrun by the piston during movement of the same, the check valve control for one of said connections comprising a check valve element carried by said pressure device and effective to delay the opening of said valve until the delivery of pressure to said pressure device through the other connection and the check valve control for the other one of said connections comprising a valve relative to which said pressure device is bodily movable but actuated by said pressure device to a position in which pressure is admitted thereby to said pressure device.

70 14. In a motor, in combination, a cylinder, a piston reciprocable therein, means for continuously venting one end of said cylinder, and means for controlling admission and exhaust with respect to the opposite end of said cylinder

including an admission valve opened by the pressure prevailing in the working end of the cylinder just prior to admission and an exhaust valve whose closing is controlled by motor back pressure and means for effecting opposite movements of said valves by working pressure from the cylinder having plural cylinder connections for each valve controlled by piston movement at widely separated points in such movement, one connection for each valve controlled by a check valve moving bodily with the valve whose functioning it controls.

15. In a motor, in combination, a cylinder, a piston reciprocable therein, means for continuously venting one end of said cylinder, and means for controlling admission and exhaust with respect to the opposite end of said cylinder including an admission valve opened by the pressure prevailing in the working end of the cylinder just prior to admission and an exhaust valve whose closing is controlled by motor back pressure and means for effecting opposite movements of said valves by working pressure from the cylinder having plural cylinder connections for each valve controlled by piston movement at widely separated points in such movement, one connection for each valve controlled by a check valve and each valve having an element moving therewith to impinge and move said check valve.

30 16. In a motor, in combination, a cylinder, a piston reciprocable therein, means for continuously venting one end of said cylinder, and means for controlling admission and exhaust with respect to the opposite end of said cylinder including an admission valve and an exhaust valve and means for effecting opposite movements of said valves including means for effecting one valve movement of each valve by working pressure from the cylinder including plural cylinder connections for each valve controlled by piston movement at widely separated points in such movement, one connection for each valve controlled by a check valve moving bodily with the valve whose functioning it controls.

45 17. In a motor, in combination, a cylinder, a piston reciprocable therein, means for continuously venting one end of said cylinder, and means for controlling admission and exhaust with respect to the opposite end of said cylinder including an admission valve and an exhaust valve and means for effecting opposite movements of said valves including means for effecting one valve movement of each valve by working pressure from the cylinder including plural cylinder connections for each valve controlled by piston movement at widely separated points in such movement, at least one connection for each valve controlled by a check valve and each valve having an element moving therewith to impinge and move said check valve.

50 18. In a motor, in combination, a cylinder, a single-acting piston reciprocable therein, means for continuously venting one end of said cylinder, and fluid distribution means therefor including an admission valve opened by the pressure prevailing in the working end of the cylinder just prior to admission, and controlling means for said valve including means providing a throwing area to close the valve, a connection from said area with the cylinder bore uncovered by the working face of the piston at substantially the moment of desired cut-off, a connection from said area with the cylinder bore uncovered by the non-working face of the piston at substan-

- tially the moment of desired admission, a check valve having a fixed locus controlling said first mentioned connection, and a check valve element bodily movable with said admission valve controlling said second mentioned connection.
19. In a motor, in combination, a cylinder, a single-acting piston reciprocable therein, means for continuously venting one end of said cylinder, and fluid distribution means therefor including an exhaust valve whose closing is controlled by motor back pressure, and controlling means for said exhaust valve including means providing a throwing area to open said valve, a connection from said area with the cylinder bore uncovered by the working face of the piston at substantially the moment of desired release, a connection from said area with the cylinder bore uncovered by the non-working face of the piston at substantially the moment of desired compression, a check valve having a fixed locus controlling the first of said connections, and a check valve element bodily movable with said exhaust valve controlling the latter of said connections.
20. In a motor, in combination, a cylinder, a single-acting piston reciprocable therein, means for continuously venting one end of said cylinder, and fluid distribution means therefor including an admission valve opened by the pressure prevailing in the working end of the cylinder just prior to admission, and controlling means for said valve including means providing a throwing area to close the valve, a connection from said area with the cylinder bore uncovered by the working face of the piston at substantially the moment of desired cut-off, a connection from said area with the cylinder bore uncovered by the non-working face of the piston at substantially the moment of desired admission, a check valve having a fixed locus controlling said first mentioned connection, and a check valve element bodily movable with said admission valve controlling said second mentioned connection, and an exhaust valve closed by motor back pressure, and controlling means for said exhaust valve including means providing a throwing area to open said valve, a connection from said area with the cylinder bore uncovered by the working face of the piston at substantially the moment of desired release, a connection from said area with the cylinder bore uncovered by the non-working face of the piston at substantially the moment of desired compression, a check valve having a fixed locus controlling the first of said exhaust-valve-controlling connections, and a check valve element bodily movable with said exhaust valve controlling the latter of said exhaust-valve-controlling connections.
21. In a motor, in combination, a cylinder, a piston reciprocable therein, and valve mechanism for said motor including a valve and controlling means therefor having a pressure area acting to move said valve, and means for supplying pressure to said area to effect valve closure and venting pressure therefrom to permit valve opening respectively having communication with the cylinder bore at points widely spaced longitudinally of the latter and having separate communications with said area.
22. In a motor, in combination, a cylinder, a piston reciprocable therein, and valve mechanism for said motor including an admission valve and controlling means therefor having a pressure area acting to move said valve to closed position, and means for supplying pressure to said area and venting pressure therefrom respectively having communication with the cylinder bore at points widely spaced longitudinally of the latter and having separate communications with said area.
23. In a motor, in combination, a cylinder, a piston reciprocable therein, and valve mechanism for said motor including an exhaust valve and controlling means therefor having a pressure area acting to move said valve to open position, and means for supplying pressure to said area and venting pressure therefrom respectively having communication with the cylinder bore at points widely spaced longitudinally of the latter and having separate communications with said area each having a check valve associated therewith.
24. In a motor, in combination, a cylinder, a single acting piston reciprocable therein, and valve mechanism for said motor including a valve having constantly a bias in one direction and controlling means therefor having a pressure area acting to move said valve in the opposite direction, and means for supplying pressure to and venting pressure from said area including a passage for supplying pressure to said area to initiate but not complete such opposite movement and a passage for venting pressure from said area to permit reverse movement, said passages respectively having check-valve-controlled communications with the cylinder bore at points widely spaced longitudinally of the latter, said pressure venting passage at a point near the beginning of the working stroke of the piston and said pressure supplying passage at a point near the opposite end of the cylinder.
25. In a motor, in combination, a cylinder, a single acting piston reciprocable therein, and valve mechanism for said motor including an admission valve having controlling means including a pressure area for moving said valve to closed position, means for opening said valve when pressure is vented from said area, and means for supplying pressure to said area to close said valve and venting pressure therefrom to permit valve opening including connections having check-valve-controlled communication with the cylinder bore at points widely spaced longitudinally of the latter, the pressure venting means at a point near the beginning of the working stroke of the piston and the pressure supplying means including a communication at a point near the opposite end of the cylinder for the delivery of starting pressure only to said area.
26. In a motor, in combination, a cylinder, a single acting piston reciprocable therein, and valve mechanism for said motor including an exhaust valve having constantly a bias towards closed position and controlling means therefor having a pressure area acting to move said valve to open position, and means for supplying pressure to said area to open said valve and venting pressure therefrom to permit valve closure including connections having check-valve-controlled communication with the cylinder bore at points widely spaced longitudinally of the latter, the pressure venting means at a point near the beginning of the working stroke of the piston and the pressure supplying means including a communication at a point near the opposite end of the cylinder and also one near the beginning of the working stroke of the piston.
27. In a motor, in combination, a cylinder, a single acting piston therein, and valve mechanism for said motor including a valve having

means for effecting movement thereof in one direction upon reduction in an opposing force, and means for providing such a force to effect the opposite valve movement including a pressure fluid actuated element, and means associated therewith including a connection for transmitting pressure thereto after an initial movement of said member but ineffective until movement is started, and means for transmitting only a starting movement to said element ineffective as soon as substantial movement takes place.

28. In a motor, in combination, a cylinder, a single acting piston therein, and valve mechanism for said motor including a valve having pressure-fluid-actuated means for effecting movement thereof in one direction and movable in the opposite direction upon the rendering ineffective of said fluid actuated means, and means for rendering said fluid actuated means effective and ineffective including means governed by movements of said fluid actuated means for controlling the times of effective supply and venting of fluid relative thereto.

29. In a motor, in combination, a cylinder, a piston reciprocable therein, means for continuously venting one end of said cylinder, and means for controlling admission and exhaust with respect to the opposite end of said cylinder including an exhaust valve having associated therewith means constantly exerting thereon a yielding closing pressure and having a pressure fluid responsive actuating and controlling device associated therewith for effecting opening and controlling closing thereof, said device having a surface in continuous communication with the motor exhaust and an opposing surface periodically subjected to cylinder pressure, said latter surface having a plurality of valve-controlled connections between the same and the cylinder bore at points in the latter overrun by the piston at widely spaced positions in the travel of the latter, and said device respectively carrying and impinging upon the valves controlling said connections. 5 10 15 20
